UNITED STATES PATENT OFFICE.

HENRY CHARLES TROST, OF EL PASO, TEXAS.

VALET-SERVICE WARDROBE FOR HOTEL DOORS.

Application filed September 20, 1927. Serial No. 220,786.

The object of this invention is to provide a simple structure adapted to be built into a hotel door and to serve as a means whereby the guest occupying the room may deliver 5 to the hotel valet or other employee articles of clothing, etc., for pressing, cleaning, etc., without the personal attention of the guest, the construction being such that the guest may readily place the articles to be cleaned, 10 etc., in the wardrobe and the valet may at a later time unlock the wardrobe with a special key from the outside and thus be enabled to remove the articles from the wardrobe without disturbing the guest. After the articles 15 are cleaned, etc., the valet replaces them in the wardrobe and locks the same closed, in position for the guest to remove the articles at his pleasure. A special feature of this invention lies in the provision of means where- 20 by the wardrobe may be so adjusted as to be used as a ventilator for the room without destroying the privacy of the room for the occupant, as more fully hereinafter set forth.

In the drawing—

Fig. 1 is an outside view of a hotel door constructed in accordance with my invention;

Fig. 2 is a vertical sectional view thereof; Fig. 3 is a horizontal sectional view on the line 3—3 of Fig. 1;

Fig. 4 is a similar view on the line 4—4 of Fig. 1;

Fig. 5 is a detail perspective view of the box-like structure.

Referring to the drawing annexed by reference-characters, 5 designates a hotel door of the usual construction, except that, instead of the usual central panels and cross-rails, I mount rigidly within the door-frame 40 a wardrobe-casing consisting of a bottom-plate 6, a top-plate 7, vertical end-plates 8, an inside-plate 9 and an outside-plate 10, forming a rectangular casing fastened rigidly to the door and projecting beyond the 45 two opposite faces of the door, the covering-boards or plates 9 being parallel with the respective faces of the door.

The outside face of the plate 10 is provided, near the knob-edge of the door, with 50 a vertical opening sufficiently large to permit articles of clothing to be inserted in the cabinet and withdrawn therefrom by the valet who may have access to the cabinet from the outside corridor. This opening is 55 of less width than the cabinet and is adapted

to be closed by means of a sliding door 11. The inside wall 9 of the cabinet is provided with a similar opening 12, but this opening is staggered with reference to the outside opening, i. e., is located at the opposite, 60 hinge-edge of the door, so that the opposite wall (9 or 10) forms an opaque shield for each opening, to thereby preserve the privacy of the room.

With the structure thus described, it will 65 be seen that the guest may place the articles of clothing he desires pressed, cleaned or repaired in the cabinet through the opening 12, and that the hotel employee may remove these articles of clothing from the outside 70 by sliding back door 11. The cabinet or casing is provided with a false-bottom-board 14 which is rigidly supported at its ends upon the end-walls 8 by means of metal brackets 15. A similar board 16 is fastened, 75 by similar brackets 17, to said end-walls 8 near the top-wall 7 of the cabinet. Any suitable clothes-hanger devices may be placed within the cabinet and arranged to be supported either by the top-board 16 or the 80 side-walls 8; I have shown for this purpose a horizontal rod 18 supported by the end-walls 8.

Resting on top of the top-board 16, in the 85 space between the same and the top-wall 7, is a plate 19 which is adapted to slide on the top surface of the board 16, anti-friction rollers 20 being employed to facilitate this sliding action. One end of this board 19 is fastened to the top edge of the sliding door 90 11, and the other edge of this board 19 is fastened to another sliding door 21 which depends between the adjacent edge of stationary board 16 and the inner wall 9 of the cabinet. This door 13 is adapted to partly 95 close the inner opening 12 when the outer door 11 is opened by the valet. To give structural strength to the pair of hanging doors, I connect the lower ends of these two doors with a plate 22, which board lies between the false-bottom 14 and the main bottom 6 of the cabinet. This construction provides a box-like structure which may be readily slid back and forth without binding. To 100 lock the doors in a desired position, I provide a series of bolt-holes 23 along the top board 19, so that the depending bolt 24 of a suitable lock, mounted on the door proper, may enter. This bolt is adapted to be slid 105 from the inside by means of a knob 25 and 110

from the outside by means of a key 26, which key will of course be in the possession of an authorized employee of the hotel.

The main purpose of the sliding box-like structure is to permit this apparatus to be used for ventilating the room without destroying the privacy thereof. With this structure, it will be seen that when the outer door stands open, there will be a clear passage 10 through the cabinet for ventilation purposes. Should the outer door be opened to its fullest extent, it would be possible for persons in the outside corridor to peep into the room, were it not for the inside door 13, which, when the outer door is opened sufficiently, slides more or less across the inner opening 12 and thus blocks vision through said opening. In view of the staggered relationship of the two openings in the 20 walls of the cabinet, it is not necessary, in order to preserve privacy, to entirely close the inner opening 12 when the door 11 is opened wide, and for this reason the inner door 13 is made considerably narrower than the outer door 11, so that, no matter how wide the outer door 11 may be opened, there will always be ventilation through the cabinet. Ordinarily, i. e., when there is no clothing to be delivered to the valet, the 30 outer door 11 will stand more or less open, to thereby permit constant ventilation of the room, through the door, without destroying the privacy of the room.

What I claim as new is:

1. A service wardrobe for hotel doors embodying a casing mounted in the door and projecting from the opposite faces thereof, the outer wall of the casing being provided near one edge of the door with a vertical 35 opening and the opposite edge of the inner wall of the casing being provided with a similar opening, the two openings being thereby staggered, and a sliding door within the casing adapted to open and close the 40 outer opening.

2. A service wardrobe for hotel doors embodying a casing mounted in the door and projecting from the opposite faces thereof,

the outer wall of the casing being provided near one edge of the door with a vertical 50 opening and the opposite edge of the inner wall of the casing being provided with a similar opening, the two openings being thereby staggered, a sliding door adapted to open and close the outer opening, an inner door adapted to more or less close the inner opening, and means connecting these doors so that when one door is moved to open position the other door will be moved to closed position. 60

3. A service wardrobe for hotel doors embodying a casing mounted in the door and projecting from the opposite faces thereof, the outer wall of the casing being provided near one edge of the door with a vertical 65 opening and the opposite edge of the inner wall of the casing being provided with a similar opening, the two openings being thereby staggered, and a box-like door structure enclosed within the casing and having 70 an outside door and an inside door adapted to respectively cooperate with the outside and inner openings in the casing, and means connecting the respective upper and lower edges of these doors. 75

4. A service wardrobe for hotel doors embodying a casing mounted in the door and projecting from the opposite faces thereof, the outer wall of the casing being provided near one edge of the door with a vertical 80 opening and the opposite edge of the inner wall of the casing being provided with a similar opening, the two openings being thereby staggered, a false bottom supported within the casing, a top-board supported 85 within the casing at a distance from the top-wall of the casing, an outside door and an inside door within the casing, a top-board connecting these doors and supported anti-frictionally upon the upper board, and a bottom-board connecting these doors and lying under the false bottom. 90

In testimony whereof I hereunto affix my signature.

HENRY CHARLES TROST.
